(57) **CLAIM**

We claim the ornamental design for a wound dressing, as shown and described.

DESCRIPTION

FIG. 1 is a perspective view of the claimed design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The evenly dashed broken lines depict portions of a wound dressing and form no part of the claim. The dash dot dash broken lines depict the claim boundary and form no part of the claim.
